UNITED STATES PATENT OFFICE.

DAVID MCNAIR, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,638, dated December 27, 1881.

Application filed November 25, 1881. Term of patent 3½ years.

To all whom it may concern:

Be it known that I, DAVID MCNAIR, of Boston, in the county of Suffolk and State of Massachusetts, have invented a new and original 5 Design for a Carpet, of which the following is a specification.

The nature of my invention is fully shown in the accompanying photographic illustration.

The design consists of the free-hand floral 10 and foliage bouquets A B C D, of different sizes, arranged, as shown, on a ground ornamented by a net-work of lines forming rectangles and hexagons, the latter inclosing Greek crosses.

I claim—

The design for a carpet, substantially as 15 shown and described.

In testimony whereof I have signed my name to this specification, in the presence of two subscribing witnesses, this 23d day of November, 20 1881.

DAVID MCNAIR.
